PORTABLE PLURAL CHANNEL ELECTRONIC AMPLIFIER

Lloyd D. Ross, Jr., Cleveland, Ohio, assignor to Electronic Music Corporation, Cleveland, Ohio, a corporation of Ohio

Filed Dec. 22, 1967, Ser. No. 9,887

Term of patent 14 years

Int. Cl. D14—04

U.S. Cl. D26—14

FIG. 1

FIG. 2

FIG. 3

FIG. 1 is a perspective view of a portable plural channel electronic amplifier embodying the design;
FIG. 2 is a front elevational view of the amplifier; and
FIG. 3 is an end view of the amplifier.

The back of the amplifier presents a plane surface.

I claim:

The ornamental design for a portable plural channel electronic amplifier, as shown and described.
